(57) **CLAIM**

The ornamental design for a display insert, as shown and described.

DESCRIPTION

FIG. 1 is a perspective view of a display insert according to a first variant of the present design;

FIG. 2 is a top view of the display insert of FIG. 1;

FIG. 3 is a front side view of the display insert of FIG. 1;

FIG. 4 is a rear side view of the display insert of FIG. 1;

FIG. 5 is a bottom view of the display insert of FIG. 1;

FIG. 6 is a right side view of the display insert of FIG. 1;

FIG. 7 is a left side view of the display insert of FIG. 1;

FIG. 8 is a perspective view showing the display insert of FIG. 1 mounted in an aperture of a countertop worksurface;

FIG. 9 is a perspective view of a display insert according to a second variant of the present design;

FIG. 10 is a top view of the display insert of FIG. 9;

FIG. 11 is a front side view of the display insert of FIG. 9;

FIG. 12 is a rear side view of the display insert of FIG. 9;

FIG. 13 is a bottom view of the display insert of FIG. 9;

FIG. 14 is a right side view of the display insert of FIG. 9;

FIG. 15 is a left side view of the display insert of FIG. 9; and, FIG. 16 is a perspective view showing the display insert of FIG. 9 mounted in an aperture of a countertop worksurface.

The portions shown in broken lines form no part of the claimed design. The dash-dot broken lines denote a boundary separating the claimed design from unclaimed portions of the design, and form no part of the claimed design.

1 Claim, 8 Drawing Sheets
